UNITED STATES PATENT OFFICE.

JOHN C. GRAF, OF HOLLISTER, CALIFORNIA.

PRIMING DEVICE.

1,221,532.

Specification of Letters Patent.

Patented Apr. 3, 1917.

Application filed August 9, 1916. Serial No. 114,049.

To all whom it may concern:

Be it known that I, JOHN C. GRAF, a citizen of the United States, residing at Hollister, in the county of San Benito and State of California, have invented certain new and useful Improvements in Priming Devices, of which the following is a specification.

This invention relates to priming devices for internal combustion engines, and, while adapted particularly for use in connection with motor cycle engines, may also be used with equal facility upon automobile or even stationary gas engines.

15 The primary object of the invention is to provide a simple and improved means whereby an initial charge of combustible fluid may be introduced to the engine cylinders with expediency and with little trouble, whereby the motor may be quickly started.

20 A further object of the invention is to provide a device of this character for use in connection with motor cycles, the arrangement being such as will enable the rider or operator to manipulate the same from his position upon the saddle.

25 A still further and particular object of the invention is to provide a priming device of the above mentioned type which is of simple and inexpensive construction, which is composed of but few readily assembled parts, all so constructed and arranged as to prevent wear, breakage or derangement of the same, which is proof against becoming 30 clogged or disordered, and which will prove thoroughly efficient in the attainment of the ends for which it is designed.

With these objects in view, together with others which will appear as the description 35 proceeds, the invention resides in the novel formation, combination and arrangement of parts, all as will be described more fully hereinafter illustrated in the drawings, and particularly pointed out in the claims.

40 The invention will be best understood by reference to the accompanying drawings, wherein:

Figure 1 is a side elevation of a priming device constructed in accordance with the 45 invention, and illustrating the application of the same to a conventional type of motor cycle;

Fig. 2 is an enlarged longitudinal section taken through the primer; and

50 Fig. 3 is a top plan view of the priming device.

Referring now more particularly to the drawings, 4 indicates a fuel tank or reservoir of the motor cycle, 5 the engine cylinders thereof, and 6 the priming cups for the cylinders. The engine in the present illustration is shown as being of the two-cylinder type; however, it will be understood that the device may, with minor alterations, be rendered applicable to engines of various types 65 having one or more cylinders.

Disposed vertically within the fuel tank 4 is a tube 7, said tube projecting at its upper and lower ends beyond the upper and lower portions respectively of the tank. 70 This tube may be soldered or in any other preferred manner, secured within the tank. The lower protruding end of the tube is closed by a head 8, the latter projecting beyond the said tube and is exteriorly threaded as shown for the reception of a cap 9. This cap carries a centrally arranged and downwardly extending nipple 10, to which is secured the neck portion 11 of a three-way valve 12. The head 8 is provided with 75 a central bore 13 communicating with the nipple 10 and is cut out or rounded at its inner end as at 14 to provide a seat for a suitable plunger or valve 15 contained within the tube.

80 The valve has connected thereto oppositely extending pipes or ducts 16, one leading to each of the priming cups 6 of the engine cylinders. The valve 12 may be controlled by a suitable finger grip or plug member 17 85 as shown.

85 The upper outwardly extending portion of the tube 7 is exteriorly threaded for the reception of a cap 18, the latter being divided in its head with an aperture through which 90 the plunger 15 extends. The upper protruding extremity of the plunger 15 has threaded thereon, lock nuts 19, between which a finger grip or handle member 20 is held. An expansion spring 21 encircles 95 the plunger 15, is seated at one end against the cap 18, and engages at its opposite end with a cross pin 22 extending through the plunger inwardly from the lower end thereof. The lower end of the plunger 15 is rounded as 100 shown to correspond to the shape of the seat 14 in the head 8. Ports 23 are arranged in the wall of the tube 7 adjacent the lower end thereof, whereby the fluid fuel within the tank may have access to the interior of 105 the said tube.

In operation, the priming cup valves or

other closures, now shown in the present instance, are opened, as well as the valve 12. The plunger 15 is then lifted against the tension of the spring 21, whereupon the liquid fuel enters the passage 13, nipple 10 and passes through the valve and pipes 16 to the priming cups upon the cylinder. The cylinders are thus provided with fuel sufficient to enable the engine to be started and 10 the priming cups may then be closed. The release of the handle 20 of the primer automatically seats the plunger 15 upon the portion 14 of the head 8, whereby further passage of fluid into the pipes will be prevented. The valve 12 may or may not be closed as desired, the plunger 15 forming a 15 valve to prevent further admission of fluid to the priming cups.

From this description, it is apparent that 20 I have provided an extremely simple and yet thoroughly efficient priming means for internal combustion engines. It will be understood that additional branch pipes 16 may be used when it is desired to adapt the device 25 to engines having three or more cylinders, while the pipes may be disconnected from the valve when the device is to be used with an engine of the one cylinder type.

I have illustrated the pipes 16 in the 30 present instance as leading to the priming cups of the engine cylinders, but it will be understood that these tubes may, if desired, communicate with the interior of the intake manifold, in which case, the priming operation 35 would consist of merely opening the valve 12 and raising the plunger 15.

The valve 12 is only closed when the vehicle is not to be used for some time, or 40 when the machine is left standing where unauthorized persons may tamper with the same.

While the above is a description of the preferred embodiment of the invention, it is obvious that various changes in minor details of construction, and arrangement of parts may be resorted to, if desired, without departing from the spirit of the invention, or exceeding the scope of the claims.

What is claimed is:—

1. In a priming device, the combination 50 with an engine cylinder and the fuel tank for a motorcycle, of a tube in the tank, the tube having apertures therein, a fuel connection between the engine cylinder and the tube said connection terminating adjacent 55 to the apertures, a plunger in the tube of lesser diameter than the tube to leave a fluid passage the plunger being adapted to normally close the mouth of the fuel connection, a spring normally seating the 60 plunger, and finger pieces for unseating the plunger.

2. The combination with a fuel tank of a motorcycle and an engine cylinder, a tube 65 in the tank, a fuel connection between the engine cylinder and the tube, said connection terminating at the tube within the tank, said tube having openings adjacent to the mouth of said connection, a plunger adapted to close the mouth of the connection, a spring 70 on the plunger for holding it in such connection against the force of an explosion, finger pieces for unseating the plunger, and a valve in the fuel connection for severing 75 communication between the tube and the connection.

In testimony whereof I affix my signature in presence of two witnesses:

JOHN C. GRAF.

Witnesses:

JOHN GRAF,
S. G. BUTTON.
